AUTOMATIC AEROPLANE RELEASER

Ernest Aiello, Walla Walla, Wash., assignor of
one-half to Jean Speros Southas, Cristobal,
Canal Zone

Application October 28, 1932. Serial No. 640,067

4 Claims. (Cl. 244—2)

This invention relates to an automatic aeroplane releaser and has for the primary object the provision of means for aiding an aeroplane to rapidly obtain flight from a standing position on 5 the ground and to first provide chocks to prevent accidental forward motion of the aeroplane during the tuning or warming up of its power medium and also until sufficient pulling power has been obtained from the power medium to assure 10 rapid ascent of the aeroplane when automatically released by the device.

With these and other objects in view this invention consists in certain novel features of construction, combination and arrangement of parts 15 to be hereinafter more fully described and claimed.

For a complete understanding of my invention, reference is to be had to the following description and accompanying drawings, in which 20 Figure 1 is a fragmentary side elevation illustrating an aeroplane with an automatic releaser applied thereto and constructed in accordance with my invention.

Figure 2 is a fragmentary sectional view illustrating the same with the releaser occupying a position to elevate the forward end of the aeroplane from the ground.

Figure 3 is a detail sectional view taken on the line 3—3 of Figure 1.

30 Figure 4 is a fragmentary sectional view showing the releaser in a position as the aeroplane assumes flight.

Figure 5 is a transverse sectional view showing the aeroplane elevated by the releaser.

35 Figure 6 is a detail sectional view illustrating one of the supporting legs.

Figure 7 is a detail sectional view showing one of the journals for the releaser to the aeroplane.

Figure 8 is a fragmentary diagrammatical view 40 showing various positions assumed by the aeroplane during the operation of the releaser.

Referring in detail to the drawings, the numeral 1 indicates a fragmentary portion or forward part of an aeroplane fuselage having arranged at the front end thereof the usual propeller 2. A running gear 3 is secured to the fuselage 1 rearwardly of the forward end thereof and includes the usual depending members 4 carrying axles on which ground wheels 5 are journaled, 50 the members 4 being reinforced by struts 6. The running gear 3 is located directly under the heaviest part of the fuselage.

The members 4 of the running gear are provided with journals 7 rotatably receiving the ends 55 of a shaft 8 on which are provided spaced legs 9,

each including an internally threaded section 10 carried by the shaft 8 and receiving therein a section 11. The section 11 has threaded connection with the section 10 and may be adjusted relative to the latter for the purpose of increasing and decreasing the length of the leg. Each section 11 carries a foot 12 having a roughened or knurled face 13 for contact with the ground and is adapted to bit into the latter to prevent slipping during the use of the device. 60

A cam 14 is secured to the shaft 8 and is provided with cam faces 15 and 16 arranged angularly to each other with an eye portion 17 located where the faces 15 and 16 meet. The face 16 merges into an extension 18 formed on the cam. 70

A tension member 19 is secured to the bottom of the fuselage and is shown in the form of a leaf spring with the free end portion thereof riding against the faces of the cam during the various positions occupied by the legs 9. 75

A sprocket gear 20 is secured to the shaft 8 and has trained thereover a sprocket chain 21 extending through a slot 22 in the bottom of the fuselage and is in turn trained over a sprocket wheel 23 secured to a shaft 24 journaled in bearings 25 mounted in the fuselage. A ratchet gear 26 is secured to the shaft 24, engaged by a ratchet 27 carried by a lever 28 having one end journaled on the shaft 25. The ratchet 27 is provided with a hand operated operating medium 29 carried by the lever whereby the ratchet may be engaged and disengaged with the ratchet wheel 26 and when in engagement with the latter it will lock the lever 28 to the shaft 24 so that said shaft may be rotated in either direction for the purpose of rotating the shaft 8 in a corresponding direction. 85

Spring clips 29 are carried by the fuselage 1 and normally receive and grip the legs 9 to support them in an inoperative position, as shown in Figure 1 in full lines. 90

In operation the legs are lowered to a dotted line position shown in Figure 1, bringing the feet 13 into engagement with the ground and when in this position the feet and legs act as a chock 100 to prevent accidental forward motion of the aeroplane when resting on the ground, this being desirable when tuning or warming up an engine for flight. After the engine has been tuned its speed is increased, consequently increasing the 105 pulling power of the propeller 2, causing the aeroplane to move forwardly and upwardly into an elevated position, being supported by the legs, as shown in Figure 2. This operation causes considerable power to be utilized by the engine due to 110

the fact that the pulling power must overcome the resistance offered by the weight of the forward end of the aeroplane being moved upwardly to rest upon the legs in an elevated position. Also the movement of the legs from the dotted line position in Figure 1 to that shown in Figure 2 works against the action or tension of the resistance member 19 bearing on the cam 14. The aeroplane when in a position as shown in Figure 2, as before stated, the heaviest part is supported by the legs and the tail skid of the aeroplane, positioning the fuselage in an inclined plane, ready for flight. Further increase in development of power by the power medium will cause the legs to swing rearwardly and as soon as the legs pass beyond a vertical position they move rapidly in a rearward and upward direction, suddenly releasing the aeroplane and due to the large development of power, the aeroplane rapidly moves into flight off of the ground, consequently materially aiding the aeroplane in a rapid ascent from the ground and only requiring a comparatively short travel of the aeroplane in a forward direction before ascending or leaving the ground. The legs when moved in a vertical position swing rearwardly and upwardly, the tension element engages the face 16 and the extension 18 of the cam 14, retaining the legs in close proximity to the bottom of the fuselage and extending in a rearward direction with respect to the aeroplane. The operator or pilot after the aeroplane is in flight may manipulate the lever 28 for the purpose of swinging the legs forwardly into engagement with the clips 29 so that the legs will be supported out of the way of the running gear or wheels thereof when making a landing.

While I have shown and described the preferred embodiment of my invention, it will be understood that minor changes may be made without departing from the spirit and scope of my invention, as claimed.

Having described the invention, I claim:

1. In combination with an aeroplane having a fuselage provided with a running gear and a power medium, a shaft journalized to the running gear, combined chock and supporting means carried by the shaft, means carried by the fuselage for supporting said first means in an inoperative position, manually operated means connected to the shaft for moving said first means from an inoperative position into engagement with the ground to act as a chock for the aeroplane, said first means adapted to elevate the aeroplane into an inclined position on the developing of a predetermined amount of power from the power medium, a combined cam and tension means between the shaft and fuselage to resist the action of said first means during its movement of elevating the aeroplane and to automatically release said first means for a limited movement away from the ground to suddenly free the aeroplane for flight.

2. In combination with an aeroplane having a fuselage provided with a running gear, and a power medium, a shaft journalized to the running gear, legs carried by said shaft, a manually operated means connected to the shaft for positioning the legs either in engagement with the ground or into an inoperative position adjacent the fuselage, said legs, when in engagement with

the ground, adapted to act as a chock against forward motion of the aeroplane during the warming up or tuning of the power medium and adapted to elevate the aeroplane into an inclined position on the development of a certain amount of power by the power medium, a cam carried by the shaft, and a tension member carried by the fuselage and engaging the cam and adapted to resist the rearward swinging movement of the legs during the elevation of the aeroplane into an inclined position and adapted, after the elevation of the aeroplane and on the development of a certain amount of power, to free the legs for rearward swinging motion and automatically free the aeroplane for flight from the inclined position under the influence of the power developed by said power medium.

3. In combination with an aeroplane having a fuselage provided with a running gear and a power medium, a shaft journalized to the running gear, adjustable legs carried by said shaft, a manually operated means connected to the shaft for positioning the legs either in engagement with the ground or into an inoperative position adjacent to fuselage, said legs when in engagement with the ground adapted to act as a chock against the forward motion of the aeroplane during the warming up or tuning of the power medium and adapted to elevate the aeroplane into an inclined position on the development of a certain amount of power by the power medium, a cam carried by the shaft, and a tension member carried by the fuselage and engaging the cam and adapted to resist the rearward swinging movement of the legs during the elevation of the aeroplane into an inclined position and adapted, after the elevation of the aeroplane and on the development of a certain amount of power to free the legs for rearward swinging motion and automatically free the aeroplane for flight from the inclined position under the influence of the power developed by said power medium.

4. In combination with an aeroplane having a fuselage provided with a running gear, and a power medium, a shaft journalized to the running gear, adjustable legs carried by said shaft, feet on said legs, a manually operated means connected to the shaft for positioning the legs either in engagement with the ground or into an inoperative position adjacent to the fuselage, said feet when in engagement with the ground adapted to act as a chock against the forward motion of the aeroplane during the warming up or tuning of the power medium and adapted to elevate the aeroplane into an inclined position on the development of a certain amount of power by the power medium, a cam carried by the shaft, a tension member carried by the fuselage and engaging the cam and adapted to resist the rearward swinging movement of the legs during the elevation of the aeroplane into an inclined position and adapted after the elevation of the aeroplane and on the development of a certain amount of power to free the legs for rearward swinging motion and automatically free the aeroplane for flight from the inclined position under the influence of the power developed by said power medium.
